(57) **CLAIM**

The ornamental design for a multiple explosion proof chambers camera housing, as shown and described.

DESCRIPTION

FIG. 1 is a perspective view of a multiple explosion proof chambers camera housing showing our new design;

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a bottom perspective view thereof.

The broken lines depict portions of the multiple explosion proof chambers camera housing in which the design is embodied that form no part of the claimed design.

1 Claim, 5 Drawing Sheets
